(57) **CLAIM**

The ornamental design for a container for serum with applicator as shown and described.

DESCRIPTION

FIG. 1 is a perspective view of a container for serum with applicator showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is an enlarged view thereof along the line 8-8 in FIG. 2;

FIG. 9 is an enlarged view thereof along the line 9-9 in FIG. 4;

FIG. 10 is a cross-sectional view thereof along the line 10-10 in FIG. 9; and,

FIG. 11 is an enlarged view thereof for the dashed line box 11 in FIG. 10.

The evenly-spaced broken lines shown in FIGS. 1-5 and 10-11 illustrate portions of the container for serum with applicator that form no part of the claimed design. The dash-dot-dash broken lines shown in FIGS. 10 and 11 illustrate the boundary of the enlarged view of FIG. 11 from FIG. 10.
